United States Patent Office.

JACOB M. AUSTIN, OF YORK, PENNSYLVANIA, ASSIGNOR TO HIMSELF AND
WILLIAM TASH, OF SAME PLACE.

Letters Patent No. 99,811, dated February 15, 1870.

IMPROVED SOAP MIXTURE.

The Schedule referred to in these Letters Patent and making part of the same.

To all whom it may concern:

Be it known that I, JACOB M. AUSTIN, of the city and county of York, in the State of Pennsylvania, have invented a new and useful Improvement in Soap Mixtures; and I do hereby declare the following to be a full and correct description of the same, sufficient to enable others to make it.

I boil six (6) quarts of soft or rain water, into which I pour one (1) ounce of beef gaul, three (3) ounces of sal soda, one-half ($\frac{1}{2}$) ounce of borax, and one (1) table-spoonful of fine salt. To this I add seven (7) pounds of Colgate's opopoeiopoei which has been shaved fine. I stir the mixture briskly, and let it boil about twenty (20) minutes, until all the ingredients are well dissolved. I then take it from the fire and stir into the mixture one (1) gill of equal parts of ammonia, alco-

hol and turpentine, being one-third ($\frac{1}{3}$) of a gill of each, and add, to perfume the mixture, one (1) ounce of sassafras. While warm I pour into square pans or boxes. When cold the soap is ready for use.

To color the soap ultra-marine and Chinese vermillion may be used.

Having thus described my invention,

What I claim as new, and desire to secure by Letters Patent, is—

The soap mixture, consisting of the ingredients in substantially the proportions herein described.

JACOB M. AUSTIN.
